UNITED STATES PATENT OFFICE.

WALTER JOHN BRIGG, OF EPPING, SYDNEY, NEW SOUTH WALES, AUSTRALIA.

SHOE.

Application filed July 15, 1925. Serial No. 43,863.

This invention relates to attaching means for attaching wear receiving elements, such as heels, toe caps and soles to shoes.

An object of this invention is to provide improved means especially adapted for attaching a wear receiving element, such for example as a heel, to a shoe, by a direct sliding movement of the parts to be attached, and without the use of attachment plates or similar means which tend undesirably to stiffen the wear element.

A further object of this invention is to provide a device of this character which may be used selectively either with or without the attaching elements that is to say, to provide a wear element which may be nailed upon a shoe in the ordinary manner, or in which the advantage may be had of attaching it without the nails, or which may be attached to a shoe by detachable attaching means supplemented by nails cooperating therewith.

A further object of this invention is to provide a device of this character which may be molded, and in which the mold is adapted to improve the character of the heel when it is not desired to use the attaching devices.

A further object of this invention is to provide an improved wear element for a shoe.

With the foregoing and other objects in view I have invented the device illustrated in the accompanying drawings, in which:

Figure 1 is a top plan view of a detachable heel.

Figure 2 is a like view to Figure 1, when a heel is molded without the attaching means.

Figure 3 is a fragmentary bottom plan view showing the attaching means as affixed to the shoe.

Figure 4 is a fragmentary section through a heel provided with my device.

Figure 5 is a transverse section through the bottom of a shoe heel provided with my device, showing the co-action of the attaching means.

Figure 6 is a top plan view of one of the mold sections.

Figure 7 is a section on line 7—7 of Figure 6.

Figure 8 is an enlarged section view of a portion of Figure 7 showing an attaching device in position for molding.

Figure 9 is a plan of a modified form of heel attaching means.

Figure 10 is an enlarged view of a detail shown in Fig. 9.

Referring to the drawings, a heel 2 or other tread or wear receiving element for a shoe is provided with a plurality of attaching pins or buttons 3, each having a flaring or headed anchoring end 4 embedded in the rubber or other material composing the heel, as shown in Figs. 4 and 5. The other end 65 of pin 3 protrudes from the material of the heel and has a flaring head 6 which is spaced slightly from the adjacent surface of the heel, thus providing a space thereunder for the interlocking engagement of the similarly 70 shaped headed pins 7, protruding from the base of shoe 7'. Pin 3 is illustrated as having the form of a spool with an axial hole therethrough, but may have any other form capable of interlocking suitably with pin 7. 75 Pins 7 may be nails driven into the shoe base 7' and are held fast therein by clinching or by any other suitable means.

Pins 3' are disposed in predetermined spaced relation in a row, pins 7 being similarly arranged in a row, the two rows being preferably semi-elliptical or U-shaped so that they may be readily engaged with each other. One of the rows is preferably slightly larger than the other to permit the 85 rows to slide in relation to each other, that is, so that the heads of the pins in one row may slide past the shanks of the pins in the other row while moving the parts containing the pins into or out of attaching engagement. It will be seen that the position of the undercut heads of pins 3 and 7 is such as to form a channel along the surface of the heel or part in which they are located.

When attaching the heel to the shoe the side of heel 2 containing pins 3 is faced toward the bottom 7' of the shoe, so that the U-shaped rows of pins are similarly directed, the open end of the U of the heel row being positioned nearer to the closed end of the U of the shoe row and the channels under the heads of the pins in the two rows being substantially in the same plane. The heel and shoe base may then be slid into engagement by direct sliding in said plane, sufficient force being applied to insure that the shanks and heads of the pins in one row may escape by the shanks and heads of the pins in the other row. It is thus possible to move the heel from a predetermined position remote from the shoe base 7' along a substantially linear path leading directly to

a position wherein the heads of pins 3 and 7 interlock with each other and the heel is attached to the shoe, as shown in section in Fig. 5.

5 The collar or washer 5 is preferably movable with respect to pin 3 and surrounds the shank of pin 3 to form a yielding guard adjacent to the shank of the pin to distribute the pressure between heel 2 and the head of 10 pin 7 abutting thereon and for protecting the heel from wear due to relative movement of pins 7 and heel 2 when walking with the heel or when subjecting it to the ordinary forces encountered in use. Furthermore the 15 collar provides a firmer bearing than the rubber of the heel for the heads of pins 7, and aids in guiding the heads of pins 7 when attaching or detaching the heel.

Pin 3 preferably has a tubular shank 20 which provides a hole for a nail for attaching the heel to the shoe in case it is desired to supplement the attaching means provided by the peripheral or head portion 6 of pin 3 engaging with pin 7, or in case the head 25 6 fails properly to cooperate with its corresponding pin 7, or in case it is desired to depend exclusively upon nails to attach the heel to the shoe as when no pins 7 are provided in the shoe base.

30 The head of the attaching nail 8, as shown by dotted lines, Fig. 5, engages with the upper central portion of the pin 3 in a manner similar to the engagement of a nail with a nail washer in a rubber heel of usual commercial construction. It will thus be seen that the peripheral portion of end 6 of pin 3 may serve in part for attaching the heel to the shoe while the central portion at the other end of the pin may serve in part for 35 40 attaching the heel to the shoe, either or both attaching means being selectable as may be desired.

By giving the flaring end 6 of pin 3, a funnel or cone shape, the head of pin 7 more 45 readily enters the space between head 6 and collar 5. Furthermore the head of pin 7 is subjected to firm pressure between head 6 and collar 5 owing to the elasticity of heel 2, the material of which tends to become 50 compressed between end 4 and collar 5 when collar 5 and head 6 are separated. This arrangement thus insures a tight connection 55 of the heel with the shoe.

The mold for forming the heel or other 55 wear element to be attached to the shoe comprises a top plate of the usual form (not shown), provided with the desired configuration for molding the bottom or tread surface of the heel, and the bottom plate 10. 60 Plate 10 is bevelled on its upper edge at 11 and is provided with recesses on sinks 12, the bottoms 14 of which are convex in form corresponding with the form of the concave end 6 of pin 3. Pilot pin 3 arising from 65 the center of each sink 12 helps to fix the

position of pin 3 during the molding operation. Collar 5 surrounding pin 3 closes the upper portion of sink 12 and prevents the rubber or other molding material from being forced into the sink.

70

The plate 15, normally resting upon plate 10, may be suitably held in relation therewith by pilot pin 16, the upper edge of the plate being preferably bevelled at 17. Plate 15 produces a cavity 15' in the upper surface of the heel and allows the heel to yield when subjected to strains encountered in use, so that a greater resilience is produced. The bevelled portion 11 of the mold produces an upstanding edge, like the rim of a cup, surrounding the space containing pins 3 and 7 at the top of the heel, and provides a tightly closed seam between the heel and the shoe to conceal the attaching means.

75

If desired, the attaching pins 3 may be omitted, in which case the molding material fills sinks 12 and produces circular protuberances 18, Fig. 2, spaced apart in a U-shaped row corresponding with the row of pins 3 in Fig. 1. These protuberances in 90 conjunction with the recess 15' serve to provide the heel with particularly desirable resilient qualities. The heel may be attached to a shoe by nailing or other well known means.

85

95 In the modification shown in Fig. 9, I have provided a different form of pin 3' for the heel 2', the head of the pin being of semi-circular form with the nail or shank of the pin connecting with the head near its circular edge, so that the diametrical or straight portion of the head faces inwardly, a channel being formed beneath these portions in the row of pins. I also provide a pin 21, similar to pin 3', located between the arms of the U-shaped row of pins 3'. Screw 22 threaded from the inside of the shoe engages the nut 20, which may be provided with serrated edges 24, the nut being embedded in heel 2' between opposite sides 110 thereof. Pin 21 and screw 22 cooperate to hold the heel more securely to the shoe, screw 22 serving to lock the heel in position.

100

105 In the modification shown in Fig. 9, I have provided a different form of pin 3' for the heel 2', the head of the pin being of semi-circular form with the nail or shank of the pin connecting with the head near its circular edge, so that the diametrical or straight portion of the head faces inwardly, a channel being formed beneath these portions in the row of pins. I also provide a pin 21, similar to pin 3', located between the arms of the U-shaped row of pins 3'. Screw 22 threaded from the inside of the shoe engages the nut 20, which may be provided with serrated edges 24, the nut being embedded in heel 2' between opposite sides 110 thereof. Pin 21 and screw 22 cooperate to hold the heel more securely to the shoe, screw 22 serving to lock the heel in position.

110

115 It is obvious that the invention is applicable to portions of the shoe other than the heel. For example, it may be employed for attaching a sole, toe cap or other wear receiving element or other portion of the shoe. The forms of pins 3 and 7 may be varied considerably from those shown while 120 still embodying the principles disclosed herein.

I claim:

1. In combination, a shoe, a wear element therefor, each of said parts having a plurality of pins projecting therefrom, said pins in one of said parts being adapted to detachably interlock with those in said other part.

125

2. In a wear element for a shoe, a row 130

of attachment pins, each of said pins having a headed end embedded in said wear element and a headed end projecting therefrom, and a yieldable guard adjacent said pin between said projecting end and said wear element.

3. In a tread element for a shoe, a plurality of spaced attachment means, each of said means having a portion embedded in said tread element and each having a nail hole so positioned therethrough that the head of an attachment nail may engage with said means for securing said tread element to the shoe, and each of said means having a headed attachment portion projecting from said tread element and adapted for

attachment to the shoe either independently of or in cooperation with an attachment nail through said means.

4. In a tread element for a shoe, a plurality of spaced spool-shaped buttons, each having a nail hole therethrough, one end of each of said spools being embedded in said tread element, and the other end thereof projecting from said tread element, whereby said tread element may be attached to the shoe either independently of or in cooperation with an attachment nail passing through said hole.

In testimony whereof I affix my signature.

WALTER JOHN BRIGG.
